STANLEY L. FISHER, OF CHESTER, CONNECTICUT, ASSIGNOR TO THE PRATT READ PLAYER ACTION COMPANY, OF DEEP RIVER, CONNECTICUT, A CORPORATION OF CONNECTICUT.

NOTE-SHEET WINDING MECHANISM FOR PLAYER PIANOS.

Application filed September 28, 1918. Serial No. 256,066.

To all whom it may concern:

Be it known that I, STANLEY L. FISHER, a subject of the King of Great Britain, residing in Chester, county of Middlesex, State 5 of Connecticut, have invented certain new and useful Improvements in Note-Sheet Winding Mechanism for Player Pianos, of which the following is a full, clear, and exact description.

10 This invention relates to note sheet winding mechanism for player pianos and the like, and it has particular reference to means for controlling the position of the note sheet on the take-up spool when the piano is being 15 played, so that the sheet will be wound properly on said spool.

It has been customary in the past to provide the take-up spool with movable end flanges, shiftable into engagement with the 20 respective side edges of the sheet after a few layers have been wound on the latter, to insure a true and orderly winding of the paper on the spool, which is obviously a great 25 advantage in rewinding the sheet on a music roll properly after playing has ceased. In devices of this character, however, the necessity of moving the flanges has been a disadvantage, and difficulty has been encountered 30 in exerting just the required pressure on the note sheet edges at the proper time.

One of the primary objects of my present invention is to overcome these defects of prior devices and to furnish an improved note sheet winding mechanism in which a 35 suitable pressure means is adapted to act on freely movable flanges separate therefrom, in such a manner as to bring the required pressure against the note sheet edges at the right time. More particularly it is aimed to pro-

40 vide a device wherein the flanges are under normal conditions held lightly against the edges of the sheet by gravity, or otherwise, the flanges being freely movable away from each other during the preliminary winding 45 of the sheet on the take-up spool, under the action of the note sheet edges, but being held against separation by positively operated means after a few layers have been wrapped on the spool, which offer sufficient resistance

to the pressure means to prevent the crushing, or crumpling of the sheet edges. In my device, it is unnecessary to provide special means for holding the flanges normally out of contact with the sheet, and it is also unnecessary to provide a special operating device for shifting the flanges bodily, the requirements of the situation being fully met by providing a simple stop means for the flanges operating in the manner stated.

Another object of my invention is to provide a mechanism of the character stated having pressure means for the note sheet controlled from the transmission mechanism which transmits the movement of the motor shaft to the take-up spool in winding and connects said shaft with one of the music roll spindles for rewinding.

Another object of my invention is to furnish a device of the character stated, in which the pressure on the edges of that portion of the note sheet wrapped on the take-up spool is relieved positively and automatically in the operation of rewinding, so that the flanges will be free to separate as far as is required when a new roll is placed in the instrument for playing. Preferably, the stop means for the flanges is controlled directly from the rewind lever in the key slip, in such a manner that the flanges are free to separate as soon as rewinding commences. This 80 permits the paper to be pulled on to the music roll in the proper way, and the pumping of the instrument cannot affect adversely the introduction of a new sheet between the flanges, nor is it necessary to await the expansion of a pneumatic, or the like, before such sheet can be properly placed and wound on the take-up spool.

To these and other ends, the invention consists in the novel features and combinations 90 of parts to be hereinafter described and claimed.

In the accompanying drawings, Fig. 1 is a front elevation of a player piano spool box or tracker box equipped with my improvements, showing the position of the parts as the winding of the note sheet on the take-up spool is commenced.

Fig. 2 is an end view of the device shown in Fig. 1.

Fig. 3 is a bottom view, partly broken away.

Fig. 4 shows the right hand end of Fig. 1 on a larger scale, the parts being in the same position.

Fig. 5 is a view similar to Fig. 4, showing the position of the parts after a few layers 10 have been wound on the take-up spool.

Fig. 6 is an end view showing the parts in the position of Fig. 5.

Fig. 7 is the view similar to Fig. 5 showing the clutch lever shifted into its other 15 position to commence the rewinding.

Figs. 8 and 9 are sections on lines 8—8 and 9—9 of Figs. 4 and 5 respectively, and

Figs. 10, 11 and 12 are sections on lines 10—10 of Fig. 4, 11—11 of Fig. 5 and 12—12 20 of Fig. 7 respectively.

In carrying out my invention, the spool box in its general features can be of the usual construction. The box proper is shown at 20, and the usual tracker bar therein at 21, there being the usual music roll spindles 22, 23 for supporting the music roll above the tracker bar. Below the tracker bar is the customary take-up spool or drum 24, having a spindle 25 journaled in the side 25 walls of the box. In the drawings, I show a music roll 26 of the usual kind positioned between the music roll spindles 22, 23, and carrying the perforated note sheet 27 adapted to be wound on the take-up spool.

35 The transmission mechanism indicated at T, by means of which the note sheet is unwound and rewound from the motor shaft, is shown applied to the right hand end of the box in the usual location. This transmission 40 mechanism includes a rectangular frame 28, in which the motor operated drive shaft 29 is journaled. The motor itself, which may be of any preferred type, is not shown. The music roll spindle 22 is adapted to be 45 driven from the drive shaft by means of sprockets 30, 31, mounted on the drive shaft and music roll spindle respectively, and interconnected by a chain 32. The take-up spool spindle 25 extends part way into the 50 rectangular transmission frame 28 below the drive shaft, and is adapted to be driven from the drive shaft by means of a pinion 33 on the latter, driving a gear wheel 34.

55 It is understood, of course, that in playing a piece of music, the take-up spool is rotated by the motor in such a direction as to pull the sheet from the music roll and wind it up on the take-up spool, while in rewinding, the driving connection between 60 the drive shaft and the take-up spool spindle, is released, and driving connection is made between the drive shaft and the music roll to wind the sheet back onto said roll. In order to obtain these results, the sprocket 65 30 and pinion 33 are loose on the drive shaft,

but provision is made for clutching the sprocket to the shaft and simultaneously releasing the pinion, and vice versa; and provision is also made for clutching the gear wheel 34 to and releasing it from the take-up spool spindle or shaft. In the particular form shown, a collar 35 is screwed to the drive shaft in fixed relation, and a collar 36 is arranged adjacent to collar 35 in such a manner that while it is free to slide 70 lengthwise of the shaft, it cannot turn relatively to the same. The non-rotative connection between the collar 36 and the shaft is produced by providing said collar on one side with lateral pins 37, which slide freely 75 through holes in the fixed collar 35. When the collar 36 is at the extreme left hand end of its movement, the ends of the pins 37, extend into engagement with lateral pins 38 on the sprocket 30, so that the sprocket will 80 be rotated to drive the music roll. At the opposite (right hand) side of the sliding collar 36, the same is provided with pins 39 adapted to engage radial pins 40 on the hub of the pinion 33 when the sliding collar 90 is moved to the right, as shown more particularly in Fig. 4. The sliding collar is adapted to be actuated from a lever (not shown) in the key slip of the piano, by means of suitable connections. In the example 95 shown, a lever 41 is pivoted intermediate of its ends at 42 at the back of the transmission frame, and is connected at its lower end with an operating wire 43, that is in turn appropriately connected with the key slip lever. 100 The wire 43 is movable in a direction lengthwise of the piano, and it will be seen that when the parts are in the position shown in Fig. 4, a pin 44 operating in a groove 45 of collar 36, and secured to the upper end of lever 41, will hold the sliding collar or clutch member 36 in driving engagement with the pinion 33. On the other hand, when the lever 41 is in the position shown in Fig. 7, the clutch member 36 is moved to 105 the left so as to disengage and release the pinion 33, and said clutch member will be moved into driving engagement with the sprocket wheel 30, so that the latter will then be positively rotated by the drive shaft. 110

The right hand end of the take-up spindle or shaft 25, is fixed to a sleeve 46, rotatably mounted in the transmission frame in line with an independently rotatable stub shaft 47, which serves as a mounting for the gear wheel 34. The gear wheel in question is screwed to the shaft 47 at 48, the right hand end of said shaft being journaled in a part of the transmission frame and the left hand end being freely journaled in the sleeve 46 fixed to the end of the take-up spool shaft. Provision is made for placing the gear 34 in and out of driving relation to the take-up spool shaft by arranging a clutch between the said shaft and the stub shaft. In the 115 120 125 130

form shown, this clutch includes a sliding collar or clutch member 49 on the stub shaft, which is fixed in non-rotative relation to said shaft by pins 50, extending from the left hand side of the collar through holes in a second collar 51 screwed to the stub shaft. The sliding collar or clutch member 49 is provided with a groove 52 engaged by a pin 53 on the clutch lever 41. When the parts are in the position shown in Fig. 4, the clutch member 49 has its pins 50 engaged with lateral pins 54 on the end of the sleeve 46, so that the stub shaft is coupled to the take-up spool shaft, the latter being rotated by the pinion 33 and gear wheel 34. This is the playing position. When the clutch lever is in the position shown in Fig. 7, the clutch member 36 drives the sprocket wheel 30 in such a direction as to rotate the music roll to rewind the sheet thereon, the pinion 33 being then loose on the motor shaft, and the clutch member 49 being in the disengaged position, so that the take-up spool, under the upward pull of the paper, can turn independently of the gear wheel 34.

Associated with the respective ends of the take-up spool 24 are flanges or disks 55, adapted to engage the edges of the note sheet, as the same is wound up on the take-up spool. These flanges or disks, have hubs, fitting loosely on the shaft 25, adjacent the ends of the take-up spool, so that the flanges are freely movable longitudinally of the shaft. The flanges are adapted to hold the paper in a proper position on the take-up spool during the playing of the music, by preventing deviation, or wobbling of the sheet, as it winds up, but provision is made for preventing any great amount of pressure against the edges of the sheet, until a sufficient number of layers has been wound on the take-up spool to withstand the pressure without damaging the edges of the sheet. Supposing that the sheet is of the same width as the length of the take-up spool proper, or slightly wider, the flanges 55 will be lightly held against the edges of the sheet during the preliminary winding by suitable means, such as elbow levers 56, 57, pivoted intermediate of their ends at 58 to the lower part of the spool box, and adapted to swing in a vertical plane. The upper portions of these levers have forked parts 59 embracing the shaft 25, adapted to abut against the respective hubs of the flanges to press them toward the note sheet edges. The portion below the pivot 58 of each lever extends toward the other lever, and a pin 60 on the end of lever 56 engages a slot 61 in the end of lever 57. The levers are held by gravity in the position shown in Fig. 1, with the block 62 acting as a stop. Owing to the weight of the lower parts of the levers 56, 57, the flanges are normally

pressed against the edges of the sheet with a very light pressure in case the paper starts to deviate from a straight line.

In order to provide means other than the weight of the levers 56, 57, for preventing further separation of the flanges when several layers have been wrapped on the take-up spool, and during the remainder of the playing, I provide a stop device for the flanges, which comes into action only after several layers have been wound on the spool and then remains in an arresting position relatively to said flanges. In the example shown, the stop device comprises a rock shaft 63, journaled in blocks 64 on the bottom of the spool box, and having one end arranged above the junction of the levers 56, 57. This end of the rock shaft is located at about the center of the box, being the inner end of the shaft, while the other, or outer end of the shaft extends through one of the side walls of the box beneath and in proximity to the transmission mechanism T. The inner end of the shaft 63 is provided with an arm 65, which when raised to the position shown in Fig. 1, permits free movement of the flange levers, but which when lowered as shown in Fig. 5, acts as a stop for the levers to prevent outward movement of the flanges. On the outer end of the rock shaft is fixed an arm 66 (Fig. 6), which is connected by a coil spring 67 to an adjustable hook 68 on a bracket 69 on the side of the box. The spring 67, which is adapted to be swung to one side or the other of the rock shaft axis, is arranged to hold said shaft firmly either in a position corresponding to the raised position of the arm 65, or in a position corresponding to the fully depressed position of said arm. Another arm 70 fixed to the outer end of the rock shaft adjacent to the arm 66 and located at an angle to the arm 66, is connected at its forwardly projecting end by a screw 71 to a link 72, which is in turn pivoted by a bolt 73 to a vertically movable rack 74, shown in detail in Figs. 10, 11 and 12. The rack 74, is adapted to move up and down in upper and lower guide clips 75, 76 located on the inner part of the transmission frame 28. A spring 77^a presses the rack inwardly so that its teeth 77 tend to engage a pinion 78 fixed to the hub of the sprocket wheel 30. Above the rack teeth 77 is a clear space 79, devoid of teeth and a similar clear space 80 is located beneath the series of rack teeth.

The rack 74 is adapted to be raised and lowered to a certain extent by the movement of the clutch lever 41, so as to throw the teeth 77 into, or out of engagement with the pinion 78. For this purpose, a controlling lever 81, pivoted intermediate of its ends at 82 on the lower part of the transmission frame and operatively connected with the clutch lever 41, is adapted to cooperate with 130

the arm 70. The upper end of lever 81 is connected with a pivot 83 on the clutch lever by a link 84 in such a manner that when the lower part of the clutch lever is swung to the left, the lower part of the lever 81 is swung to the right and vice versa. Below arm 70 lever 81 carries a resilient finger 85 to engage said arm and a similar resilient finger 86 is carried by lever 81 above arm 70.

10 The operation of the mechanism is as follows:—

The rewinding lever in the key slip being in the playing position corresponding to the position of clutch lever 41 in Fig. 1, and the music roll to be played being introduced between the music roll spindles in the usual manner, the end of the note sheet is fastened in the customary way to the hook on the take-up spool and pumping is commenced, actuating the motor to wind up the sheet on the take-up spool through the connections previously described. The take-up spool shaft is rotated by the pinion 33, which is locked to the drive shaft, and the intermeshing gear 34, which is locked to the spool shaft. The paper is pulled off from the music roll, causing the sprocket wheel 30 to rotate loosely about the drive shaft in the opposite direction. As soon as the motor shaft begins to rotate, the take-up spool shaft begins to rotate the take-up spool, and the pinion 78 on sprocket wheel 30 begins to move the rack 74 in a downward direction. When the clutch lever is swung to the position shown in Fig. 4, the lever 81 is so swung that its upper spring finger 86 engages the upper edge of arm 70, thereby pulling the rack 74 down into such a position (Fig. 10) that its lowermost tooth engages pinion 78. Then as the winding on the take-up spool commences, the rack is lowered by the rotation of the pinion 78 in a counter-clockwise direction (Fig. 6), through the chain connection 32 with the unwinding music roll. As the winding continues, the rack is thrown down by the pinion to the extent shown in Fig. 11, until the pinion reaches and rotates freely in the clear space 79, above the rack teeth. By the time the rack reaches this position, the rock shaft 63, through the connections described, will have been moved to the position shown in Fig. 5, so that its inner end portion, or arm 65, lies in close proximity to the junction of the levers 56, 57. This prevents upward movement of the lower end of the levers, and therefore prevents separation of the flanges. By this time several layers of paper have been wound on the take-up spool, and there is no objection to stopping the flanges rigidly, owing to the fact that a sufficient body of paper is present on the spool to resist a damaging pressure. The flanges are held fixed in position during the remainder of

any deviation and winds up truly and accurately on the spool. The rack occupies the position shown in Fig. 11 substantially throughout the playing of the piece of music, said rack reaching its lowermost position about the time, or soon after, the first note openings come opposite the tracker openings. Before this occurs, it would be objectionable to limit positively the outward movement of the flanges, as one or two layers of paper would be crushed, or damaged by contact with the flanges. This is avoided, however, by my invention, according to which provision is made for stopping the flanges by positively operated means acting at a definite time after the sheet begins to wind on the spool.

When the piece has been played, and it is desired to rewind the paper on the music roll, the clutch lever 41 is shifted in the customary manner to the position shown in Fig. 5, acting to free the take-up spool from the drive shaft and connect the latter positively with the music roll for rewinding. As the lever 41 is shifted to the position shown in Fig. 5, the lower spring finger 85 on lever 81 is shifted to lift the rack 74 to a sufficient extent to engage the uppermost rack teeth with the pinion 78 as shown in Fig. 12. The spring finger 85 does this by lifting the arm 70 to a certain extent, as will be apparent by comparing Figs. 11 and 12. The rack being then reengaged with the pinion, and the pinion being moved in a direction opposite to that first described, the rack is lifted to its fullest extent, thereby shifting the rock shaft 63 back to the position shown in Figs. 1 and 4, and removing the stop means from the flanges. The latter can then be readily separated to the necessary extent for the introduction of another music sheet, which may, of course, be considerably wider than the sheet on the roll previously played.

When the rack is raised to its uppermost position, the pinion 78 rotates freely in the clear space 80, beneath the rack teeth, but when it is desired to play again, and the clutch lever 41 is shifted back to the position shown in Fig. 5, the spring finger 85 is automatically shifted to depress arm 70 sufficiently to reengage the pinion with the rack as shown in Fig. 10. The operations described will be repeated in the playing and rewinding of the next roll.

Various changes can be made in the details and construction without departing from the scope of my invention as defined in the claims.

What I claim is:

1. The combination of a spool, oppositely movable flanges at the ends of the same, means for limiting the movement of the flanges away from the ends of the spool, and mechanical means for setting said flange

limiting means in operation at a predetermined time.

2. The combination of a spool, a sheet restraining means at each end of the same movable relatively to said spool, means for limiting the movement of said restraining means away from the ends of the spool, and mechanical means for placing said limiting means in and out of operation.

10 3. The combination of a spool, a sheet restraining means at each end of the same movable relatively to said spool, means for limiting the movement of said restraining means away from the ends of the spool, and means for placing said limiting means in and out of operation at predetermined times in the winding and rewinding of the sheet.

4. In sheet winding mechanism, a spool, movable flanges at the ends of the same, means urging said flanges toward each other and lightly against the edges of the sheet, and means for preventing the movement of said flanges in a direction away from said spool, said last named means being movable into and out of operative position by the turning of the take-up spool.

5. In sheet winding mechanism, a spool, gravity operated pressure means at the end of the same normally pressing lightly against the edge of the sheet on the spool, means for preventing movement of said pressure means away from the edge of the sheet, and means for placing said preventing means in operation positively at a predetermined time in the winding of the sheet on the spool.

6. The combination with a spool box having music roll spindles, a tracker bar, a take-up spool, and a movable note sheet guiding device associated with the take-up spool, of a drive shaft, means associated with said drive shaft for winding and rewinding the sheet, and means for limiting the movement of said sheet guiding device actuated from the winding and rewinding mechanism.

7. The combination with a spool box having music roll spindles, a tracker bar, a take-up spool, and a movable pressure device associated with the take-up spool to guide the note sheet, of a drive shaft, means associated with said drive shaft for winding and rewinding the sheet, and controlling means for said movable pressure means actuated by the rotation of the take-up spool to prevent movement of the pressure means under the influence of the note sheet edge at a predetermined time in the winding of the sheet on the take-up spool.

60 8. In note sheet winding mechanism, the combination with music roll spindles, a tracker bar, a take-up spool, a longitudinally movable sheet engaging flange at the end of the take-up spool, a drive shaft, and means for winding and rewinding the sheet

from the drive shaft, of means controlled by the rotation of the take-up spool and acting on said flange for imposing and relieving pressure at the edge of the note sheet.

70 9. In note sheet winding mechanism, music roll spindles, a tracker bar, a take-up spool, longitudinally movable flanges at the ends of the take-up spool, a drive shaft, transmission mechanism for winding and rewinding the sheet by the rotation of the drive shaft, and flange controlling means controlled from said transmission mechanism.

10 10. In note sheet winding mechanism, music roll spindles, a tracker bar, a take-up spool, longitudinally movable flanges at the ends of the take-up spool, a drive shaft, transmission mechanism for winding and rewinding the sheet by the rotation of the drive shaft, and flange controlling means controlled from said transmission mechanism to impose a predetermined pressure on the edge of the sheet only after several layers have been wound on the take-up spool and to relieve the pressure on the edge of the sheet automatically as the sheet is rewound on the music roll.

11. In note sheet winding mechanism, music roll spindles, a tracker bar, a take-up spool, movable sheet guiding flanges at the ends of the take-up spool, means for pressing said flanges against the sheet edges, a drive shaft, transmission mechanism for winding and rewinding the sheet by rotation of the drive shaft, and power operated means for relieving the pressure of the flanges against the sheet edges automatically on the rewinding.

12. In note sheet winding mechanism, music roll spindles, a tracker bar, a take-up spool, longitudinally movable sheet guiding flanges on the take-up spool, a drive shaft, transmission mechanism for connecting the drive shaft with either the take-up spool or the music roll for winding or rewinding, and stop means for said flanges controlled from said transmission mechanism.

13. In note sheet winding mechanism, music roll spindles, a tracker bar, a take-up spool, longitudinally movable sheet guiding flanges on the take-up spool, a drive shaft, transmission mechanism for connecting the drive shaft with the take-up spool or with the music roll for winding or rewinding, and stop means for said flanges controlled from said transmission mechanism to prevent further separation of the flanges when several layers have been wound on the take-up spool and to relieve the pressure of the flanges against the note sheet when the transmission mechanism is manipulated to rewind the sheet on the music roll.

14. In note sheet winding mechanism, music roll spindles, a tracker bar, a take-up

spool, longitudinally movable sheet guiding flanges on the take-up spool, a drive shaft, transmission mechanism adjustable for winding or rewinding from the drive shaft, 5 means for arresting the outward movement of the flanges, and means operable by said transmission mechanism for moving said arresting means to an inoperative position automatically when the transmission mechanism is shifted to rewinding position.

10 15. In note sheet winding mechanism, music roll spindles, a tracker bar, a take-up spool, longitudinally movable flanges on the take-up spool to cooperate with the note sheet, transmission mechanism, and means operative positively from the transmission mechanism for forcibly restraining the edges of the note sheet on the take-up spool only after several layers have been wound on said 20 spool.

16. In note sheet winding mechanism, music roll spindles, a tracker bar, a take-up spool, longitudinally movable flanges on a take-up spool to cooperate with the note sheet, a drive shaft, transmission mechanism for driving either the take-up spool or the music roll from said motor shaft, and a 25 positively operated means actuated from said transmission mechanism for imposing a predetermined pressure on the note sheet edges through said flanges at a predetermined time in the winding of the sheet on the take-up spool.

17. In a device such as described, a spool, movable end flanges for said spool, levers for controlling the position of said flanges, and mechanically controlled stop means adapted to act on said levers to prevent separation of the flanges.

40 18. A spool having movable flanges, stop means for preventing the separation of said flanges, and mechanical means for moving said stop means slowly into operative position during the preliminary winding and holding it in that position during the remainder of the winding operation.

19. In note sheet winding mechanism, a take-up spool, longitudinally movable sheet guiding flanges on said spool, means for nor-

mally pressing said flanges lightly against the edges of the note sheet, and means operable at a predetermined time in the winding of the sheet for increasing the pressure of said flanges upon said note sheet.

20. In note sheet winding mechanism, a take-up spool, longitudinally movable sheet guiding flanges on said spool, means for normally pressing said flanges lightly against the edges of the note sheet, and power operative means for increasing the pressure of said flanges upon said note sheet.

21. In a note sheet winding mechanism, a take-up spool, and a sheet restraining device associated therewith, said sheet restraining device being actuated to restrain the note sheet by the turning of the take-up spool.

22. In a note sheet winding mechanism, a take-up spool, and a sheet restraining device movable into and out of operative position, and sheet restraining device being moved into operative position by the turning of the take-up spool.

23. In a note sheet winding mechanism, a take-up spool and a sheet restraining device associated therewith, said device being delayed in its action, and controlled therein by the winding of the note sheet.

24. In combination, a tracker bar, a take-up spool, a sheet restraining device associated therewith and movable into and out of operative position, a note sheet, and means for causing said note sheet to move over the tracker bar, including a rotating shaft, said sheet restraining device being moved into operative position by the rotation thereof.

25. A web guiding device, including a spool operatively mounted to wind the web thereon, a web restraining device associated with said spool and movable into and out of operative position, and means for winding the web upon said spool, including a rotating shaft, said web restraining device being moved into operative position by the rotation of the shaft.

In witness whereof, I have hereunto set my hand on the 23rd day of Sept., 1918.

STANLEY L. FISHER.
